[57] CLAIM

The ornamental design for an amalgam well used in dentistry, substantially as shown and described.

DESCRIPTION

FIG. 1 is a perspective view of an amalgam well used in dentistry showing my new design;

FIG. 2 is a top plan view thereof;

FIG. 3 is a bottom plan view;

FIG. 4 is a cross-section taken on line 4—4 of FIG. 2;

FIG. 5 is an expanded perspective view for clarity of illustration ; and

FIGS. 6 to 8 are top views showing the components comprising the well for clarity of illustration.

*Fig. 1.**Fig. 4.**Fig. 2.**Fig. 3.**Fig. 6.**Fig. 5**Fig. 7.**Fig. 8.*
